BUILDING CONSTRUCTION

William J. Erdner, River Rouge, Mich.

Application May 1, 1935, Serial No. 19,318

6 Claims. (Cl. 72—1)

This invention relates to building constructions and refers more particularly to fabricated building constructions composed of prefashioned units.

One of the principal objects of this invention is to improve generally building constructions of the type set forth, by providing framework having weight supporting structural elements spaced from each other to permit sliding prefashioned units of convenient size therebetween in such a manner that the units are not only guided, but are also held in assembled relation by the structural elements and, in addition, by providing the units with portions overlapping the exterior surfaces of the elements. The foregoing is particularly advantageous in constructions where the preformed units are of fireproof material, such as concrete, since it protects the weight supporting structural elements from intensive heat and thereby prevents buckling of the elements.

Another advantageous feature of the present invention consists in the provision of a building construction having weight supporting columns and having floor supporting elements secured to, but spaced from the columns a sufficient distance to provide for extending portions of the prefashioned units along the inner sides of the columns, as well as along the outer sides thereof.

A further object of the present invention relates in the provision of a building construction of the character previously set forth rendering it possible to preform the window, door and chimney openings in the units, prior to securing the latter in assembled relation with the structural elements of the building.

The foregoing, as well as other objects, will be made more apparent as this description proceeds, especially when considered in connection with the accompanying drawings, wherein:

Figure 1 is a fragmentary horizontal sectional view through a portion of a building constructed in accordance with this invention;

Figure 2 is a cross sectional view taken on the line 2—2 of Figure 1;

Figure 3 is a cross sectional view taken on the line 3—3 of Figure 1; and

Figure 4 is a semi-diagrammatical elevational view illustrating the manner in which one wall of a building may be assembled in accordance with this invention.

In Figure 1 of the drawings, the reference numeral 10 designates one side wall assembly of the building, while the reference numeral 11 indicates another side wall assembly and the numeral

12 indicates the floor structure supported by the wall assemblies. In the present instance, the wall assemblies are fireproof and are built-up from steel structural elements 13 and prefashioned units 14. The steel structural elements 13 are the principal load carrying members and are preferably, although not necessarily in the form of H-section columns, while the units 14 are in the form of pre-cast concrete slabs.

As shown particularly in Figure 4, the H-section columns 13 are secured at the lower ends to the footing 15 in predetermined spaced relationship with the sides of the H disposed in planes parallel to the planes of the inner and outer surfaces of the associated slabs 14. As will be observed from Figure 1, the space between adjacent columns 13 is so determined as to provide for sliding a slab 14 therebetween, in such a manner that the opposite sides of the H of each of the columns serves to guide the slabs in place. In this connection, it is to be noted that the opposite vertical edges of the slabs 14 are recessed as at 16 throughout the length thereof, to provide for receiving the columns 13. The width of the recesses 16 is sufficiently greater than the width of the columns 13 for readily sliding the slabs in place between adjacent columns, and the depth of the recesses is so determined that the recess in the edge of one slab will cooperate with the recess in the edge of the adjacent slab to substantially enclose the intervening column. After the slabs 14 are assembled with the columns, and are properly positioned with respect to each other, the spaces around the columns are filled with concrete or some other suitable filler by pouring the same into the recesses 16. This construction provides for substantially completely embedding the columns in the side walls of the building and, in addition, serves to integrally secure the concrete slabs together. Embedding the weight supporting columns in a fire-proof material such as concrete, is extremely advantageous insofar as fire hazard is concerned, in that it shields the columns from intensive heat and, as a consequence, prevents failure of the side walls by buckling of the columns.

One particular type of corner construction is also shown in Figure 1, and as will be observed embodies an H-section column 17 identical in construction to the columns 13 previously described. However, in view of the fact that the side wall 11 extends at substantially right angles to the wall 10, the end slab 18 of the former wall is guided in place by an angular structural element 19 having one flange secured to the H-

section column, and having the other flange extending in the direction of the slab 18 for engagement in the recess 20 formed in the adjacent edge of the slab 18. The recess 21 in the end slab 22 5 of the wall 10 is identical to the recess 20 in the slab 18, and both the recesses are for the same purpose as the recesses 16 described above. In other words, the end slab 22 of the wall 10 is guided in place by the opposite sides of the H- 10 section column 17 in the same manner as the slab 14 is guided, and the end slab 18 of the wall 11 is guided in place by the angle strip 19 welded or otherwise permanently secured to the H-section 17. However, the outer walls of the recesses 20 15 and 21 are extended to compensate for the corner, and the space defined by the recesses is filled with concrete or other suitable material in the same manner as the recesses 16 are filled.

As previously stated, the floor structure 12 is 20 also supported from the H-section columns, and this is accomplished in the present instance by the following construction. The floor structure is designated in the drawings by the reference character 12 and is secured to the columns, by 25 means of gusset plates 25. As shown particularly in Figure 1, the gusset plate 25 associated with each H-section column is disposed in the same plane as the bar of the H, and the outer edge thereof is welded throughout the length to the 30 inner side of the H-section. The gusset plates 25 extend inwardly beyond the walls through the spaces provided between adjacent slabs and are bolted or otherwise suitably secured to the floor structure. In connection with the wall 10, the 35 inner portion of each gusset plate is secured to a structural element of I-shaped cross section, which forms one of the floor beams and is supported with the web 27 lying in a vertical plane. In detail, the inner portion of each gusset plate 40 overlaps the outer end portion of the web 27, and is bolted or otherwise permanently secured thereto in the field. The outer ends of the I-beams 26 are interconnected, by means of inwardly opening substantially channel-shaped struts 28 45 secured to the webs 27 of the I-beams, by means of suitable angle brackets 29. The floor or I-beam adjacent the wall 11 is connected to the outer end of a floor channel 30, by means of a strut 31 identical in construction to the strut 28, 50 and having the opposite ends, respectively, permanently secured to the floor channel and I-beam by means of angle brackets 32. The floor channel 30 is spaced inwardly from the wall 11, in the same manner as the strut 28, and is 55 secured to the H-section column 17 at the corner, by means of one of the gusset plates 25, in the same manner as the I-beams 26 are secured to the columns 13. It may be pointed out in this connection that the gusset plates 25 for securing 60 the floor channel 30 to the columns embedded in the wall 11 differ in detail from the gusset plates employed in connection with the wall 10, in that the inner ends of the former are bent laterally to provide attaching flanges 35, and the latter 65 are bolted to the outer surface of the base of the floor channel 30.

Thus from the foregoing, it will be observed 70 that I have provided a fabricated building construction composed of preformed units capable of being expediently erected at a minimum cost and including wall sections having the desired door and window openings prefashioned therein. It will also be apparent from my improved construction previously described, that the columns 75 or weight supporting structural elements are

thoroughly protected from intensive heat and, as a consequence, will not buckle readily in case of fire.

What I claim as my invention is:

1. In a building construction, a load supporting column, preformed wall sections on opposite sides of the column and having portions on adjacent edges thereof cooperating to substantially enclose the column, floor structure including a strut extending in the same general direction as the wall section and spaced inwardly therefrom, and means for supporting the floor structure from the column including a gusset plate extending inwardly from the column between the adjacent edges of the wall sections and secured to the strut. 10

2. In a building construction, a wall unit including a load supporting column substantially H-shaped in cross section supported with the bar of the H disposed in a plane extending substantially perpendicular to the plane of the wall, floor structure spaced inwardly from the column, and means for securing the floor structure to the column including a gusset plate disposed in the plane of the bar of the H and having the outer 20 and inner edges respectively secured to the column and floor structure. 25

3. In a building construction, a load supporting column, preformed wall sections on opposite sides of the column and having portions on adjacent edges thereof cooperating to substantially enclose the column, floor structure comprising supporting beams having the outer ends spaced inwardly from the wall sections, and means for supporting the beams from the column including a gusset plate having the outer edge permanently secured to the column and having the inner edge spaced inwardly beyond the wall sections and secured to the supporting beams. 30

4. In a building construction, a wall unit including a load supporting column substantially H-shaped in cross section supported with the bar of the H disposed transversely of the wall, preformed wall sections on opposite sides of the column having portions on adjacent edges thereof slidably engageable with opposite sides of the H-section column in overlapping relation to said sides, floor structure including a supporting beam having the outer end spaced inwardly from the wall sections, and means for securing the floor 45 structure to the column comprising a gusset plate disposed in the plane of the bar of the H-section column and extending inwardly from the latter between the adjacent edges of the wall sections and secured to the supporting beam. 50

5. In a building construction, a pair of laterally spaced load supporting columns, a floor structure spaced inwardly from the columns, a member connecting the columns to the floor structure, and a preformed wall section having 60 portions at opposite ends overlapping the opposite sides of the columns to one side of the floor supporting members and slidably engageable with the columns. 55

6. In a building construction, a load supporting column, preformed wall sections on opposite sides of the column and having portions on adjacent edges thereof slidably engageable with the column and cooperating to substantially enclose the latter, floor structure spaced inwardly from the wall sections, and means extending inwardly from the column between adjacent edges of the wall sections and secured to the floor structure for supporting the latter. 65
